(57) **CLAIM**

The ornamental design for a bottle opener and lighter holder, as shown and described.

DESCRIPTION

FIG. 1 is a top perspective view of a bottle opener and lighter holder;

FIG. 2 is a front elevation view thereof;

FIG. 3 is a back elevation view thereof;

FIG. 4 is a top plan view thereof;

FIG. 5 is a bottom plan view thereof;

FIG. 6 is a left elevation view thereof;

FIG. 7 is a right elevation view thereof; and,

FIG. 8 is an environmental drawing showing the bottle opener and lighter holder.

The broken lines showing a lighter, bottle and bottle cap depict environmental subject matter only and form no part of the claimed design.
